UNITED STATES PATENT OFFICE.

ROBERT P. SWEENEY, OF UNION, SOUTH CAROLINA.

AIR-INDUCTION-CLEANING APPARATUS.

Application filed June 18, 1922. Serial No. 568,830.

To all whom it may concern:

Be it known that I, ROBERT P. SWEENEY, a citizen of the United States, residing at Union, in the county of Union and State of South Carolina, have invented certain new and useful Improvements in Air-Induction Cleaning Apparatus, of which the following is a specification.

This invention relates to air induction cleaning apparatus for cleaning industrial plants, houses, or other places where lint, dust, waste, etc., collects, and to other uses. It is particularly adapted for cleaning textile factories of the light trash mixed with lint dust and refuse that ordinarily collects on and under the machinery used in those factories, and on walls, floors, ceilings, shafting pulleys, etc.

One feature of the invention relates to an arrangement whereby a waste collecting bag of maximum size relative to the size of the framework of the apparatus may be employed and whereby the bag may be easily attached to and disconnected from the machine.

Another object of this invention is to open up the cotton waste, etc., picked up by the cleaner and to put this waste in a fluffy condition. I have found that when this waste is drawn in by the suction end of my Venturi tube, it passes on through the same and reaches the expanding portion of said tube, and this expanding portion allows the air to expand; this has an expanding effect on the fibrous material of the waste that is being conveyed; this also serves to fluff up and bloom up the fibrous material and to pull the individual fibres apart, the fibrous material being completely impregnated with the air which is in process of expanding at this point. This renders the material of much higher manufacturing value in the after process of manufacture. It also renders the impurities contained in the fibrous material more readily removable.

Another object of the invention is to so arrange the Venturi tube, waste collecting chamber and parts as to employ the centrifugal motion of the air together with the downward pressure of air to distribute and pack the waste material in the waste bag, thereby greatly increasing the capacity of the waste bag.

Another object of the invention is to so mount the apparatus that it can be con-

veniently pushed in sharp turns around the machinery being cleaned.

Another object of the invention is to so construct the apparatus frame that it will have the maximum strength and endurance for the work in which it is to be used.

Another object of the invention is to provide for quick attachment and detachment of the apparatus from the waste collecting hose or the source of air supply.

Another object of the invention is to so arrange the Venturi tube parts of the apparatus as to get the maximum efficiency from the air pressure employed.

Another object of the invention is to so construct the parts of the framing as to relieve strains on the pipe connections.

Another object of the invention is to provide a framework relatively long compared with its width so that it can pass in narrow passages between the machines being cleaned.

Another object of the invention is to regulate the speed of the passage of the air through the machine by properly regulating the pressure at the discharge orifice.

With the foregoing objects outlined and other objects in view which will appear as the description proceeds, the invention consists in the novel features hereinafter described in detail, illustrated in the accompanying drawings and more particularly pointed out in the appended claims.

Referring to the drawings:

Figure 1 represents a side view of the apparatus with part of the suction hose and nozzle.

Fig. 1^a is a rear view of the machine with the suction hose and couplings and nozzle omitted.

Fig. 2 is a top plan view of the waste collecting cylinder with the top removed showing the entrance therein of the air and waste tube and its coiled construction.

Fig. 3 is a side elevation of the mechanism shown in Fig. 2.

Figs. 4, 5, 6 and 7 are sectional views of this same mechanism taken respectively on the lines 4-4, 5-5, 6-6 and 7-7.

Referring more particularly to the drawings, 1 designates what may be called the waste collecting chamber, which is usually of metal and cylindrical in shape and is provided with a top 2 having handles 3 whereby the top may be easily taken off or

put on. The top is held down tight against the waste collecting chamber. A packing ring may be placed between the under side of the top and flange on the waste collecting chamber to make it air-tight. A pipe section 4, Fig. 2, preferably of metal enters the cylindrical chamber 1 in a tangential line as shown in Fig. 2 and is coiled around within the cylindrical chamber endng approximately under the end of an inclined shelf 5, within the chamber 1. The waste laden air passing through the pipe 4 and coiled part 8 is delivered under the inclined shelf 5 which, on account of its downwardly inclined portion has a tendency to direct the waste particles as they leave the pipe towards the bottom of the cylinder 1 into the waste bag 9 through the pores of which the air escapes and at the bottom and on the sides of which the waste settles.

On the end of inclined shelf 5 is placed a deflector 5' which is inclined downwardly at a sharper angle than shelf 5. The incoming air and waste strikes this deflector and is quickly thrown to the bottom of the waste bag thereby packing the same in the bag. The centrifugal motion of the air causes the waste to be evenly distributed around the bag. The deflector also prevents too much centrifugal motion. The waste collecting chamber also serves as an expansion chamber for the incoming air and on account of its tight top, a downward pressure of air further causes the waste to be packed in the bag.

The pipe section 4 may be slightly larger at its end where it enters the waste chamber 1 than it is at the other end where it is attached to another pipe section 10 also preferably metal which may be flared slightly from its end attached to the section 4, to its other end attached to an elbow 11 preferably of metal. The approximate relative sizes which admit of variation of different cross sections of this section 10 are illustrated respectively in Figs. 4 and 5, and the size of the section 4 approximately relative to that of section 10 is illustrated in Figs. 6 and 5. These pipe sections are preferably rigidly held together and to the waste collecting chamber, the elbow section being rigidly supported on the framework.

At the end of pipe section 10 there is provided a part 12 (Fig. 5) through which extends a hole 13. The interior edge of this hole may be slightly above the bottom of pipe section 4 as shown in Fig. 3 and through the hole 13 passes a nozzle 14 of a compressed air pipe 15, preferably of metal. The end of the pipe section may be split as shown in Fig. 5 and the opposite split portions held together around the nozzle 14 by a screw, as shown. The nozzle 14 is coupled to the pipe 15 by ordinary pipe couplings and may be elevated slightly above

the bottom of the pipe section 4 and may be upwardly inclined to said bottom as shown in Fig. 3 so that when the compressed air passes from the nozzle it may be upwardly inclined to better draw the air and material being conveyed through the pipe section 10, elbow 11 and air hose 16 and suction nozzle. It will be noted in Fig. 1 that the sections 10 and 4 are given a slight inclination downwardly so that any water of condensation resulting from the sudden expansion of the air as it comes through the nozzle 14 will trickle down the pipe section 4 and escape at the end of the pipe to prevent the water from remaining in the pipe and collecting the dust and lint as it is brought in through the hose 16. However, there is provided a clean-out hole 17 in the elbow 11 as shown in Figs. 1 and 2 which may be opened and the elbow 11 and pipe sections 10 and 4 cleaned of any accumulation of lint or dust. The elbow 11 is rigidly supported by brace rods 18, 18' firmly attached to brackets 19 and 19' which in turn are attached to a band 20 passing around the waste chamber 1. The ends of this band are held by bolts 21 which may be loosened and the chamber 1 removed from the framing of the machine when desired.

Extending from the bracket 19 is a brace rod 22 slightly inclined as shown, its lower end being firmly secured to the truck 23, and a vertical rod 24 extends from the truck 23 and is attached to the bracket 19 as shown in Fig. 1, the similar bracket 19' Fig. 1^a being attached to the other side of the band 20. From this bracket 19' a vertical rod 24' extends to the truck 23. Passing from the rods 24 and 24' are brace rods 25 and 26, the rod 26 extending beyond and around the compressed air pipe 15 and the rod 25 extending beyond and around the air hose 16. It will be noticed that this rod 25, Fig. 1, will prevent any sudden transverse pull on the hose coupling 27 between the hose 16 and the lower end of the elbow 11 as the apparatus is pushed around from place to place in proximity to the machines, etc. to be cleaned. A similar brace rod to 22 is attached to bracket 19'.

Connected to the compressed air pipe 15 is a gage 29 and the pipe 26 protects the connection between the gage and the pipe from coming in contact with projections or walls as indicated in Fig. 1^a when the hose 16 is disconnected from the cleaning machine. The gage 29 will indicate to the machine attendant the pressure in the compressed air pipe 15. This pressure is regulated by an ordinary pressure regulating valve 30 and the lower part of the machine and this regulating valve is prevented from coming in contact with the machine being cleaned or a post or wall by the brace rod 25 as shown in Fig. 1.

- This regulating and reducing valve may be of the ordinary diaphragm type or any other type with the same functions and is attached to an extension of the compressed air pipe as shown in Fig. 1. Attached to the compressed air pipe is a pet cock 31 of ordinary construction which may be opened occasionally to blow out any water that might have been precipitated within the compressed air pipe 15 and which may have run down to the horizontal portion of the compressed air passage, and any water which might collect in the compressed air line.
- Within the horizontal portion of the compressed air passage 32 may be interposed an ordinary spring loaded valve 32' for cutting off the supply of compressed air between the horizontal portion 32 of the compressed air passage and the flexible compressed air hose, the end 33 of which is shown in Fig. 1. This hose is connected to the horizontal air passage 32 by an ordinary quick-change hose coupling 34, Fig. 1, whereby the waste collecting machine may be quickly separated from the source of compressed air. This source of compressed air may be a pipe, a pump, or an ordinary compressed air tank.
- The entire machine is supported on the truck 23 having wheels 35—35' with their axes passing through projections 36—36' on the lower edge of the truck. A third wheel 37 is swiveled to the truck frame thus enabling the machine to be suddenly turned in any direction and pushed about between the machines, etc. to be cleaned. A stop 38 on the front of the truck prevents tipping of the machine forward too far. The regulating valve and horizontal portion of the compressed air pipe is supported on a board 39 bolted to the uprights 24 and 24' as shown in Fig. 1^a.
- It will be noticed that the framework of the apparatus is considerably narrower than it is long so that it can go along narrow passageways between the machines, etc. being cleaned. The truck platform 23 is dish-shaped to receive the bottom of the bag, the sides 40 of the platform being cut away at the front of the truck so that the bag can be slid off the truck without raising the same. Particular attention is drawn to the way the waste chamber overhangs the truck and the way side braces 22 are placed so as not to interfere in any way with the hands of the machine operator in putting on and taking off the waste bags.
- The bag is conveniently attached to the waste chamber 1 by a cord 41 which is threaded through the hemmed part of the top of the bag and rests on a flange 42 projecting from the bottom of the waste chamber 1. By loosening the cord 41 the mouth of the bag may be opened sufficiently to pass over the flange 42 and by drawing the cord 41 the mouth of the bag may be closed and the collected waste, lint, etc. conveniently removed from the truck platform and an empty bag put in its place.
- The two ends of the draw cord on the bag may be passed through a cord fastener to automatically hold the cord tight at any desired point. The cord fastener being part of a bag equipment and of any ordinary type is not shown in the drawings as the cord is shown cut away in Fig. 1 to show flange 42.
- The hose 16 may be the ordinary flexible air suction hose made of rubber or fabric with a wire coil around it of any other type and the compressed air hose 33 may also be of the usual construction.
- As indicated in Figs. 1 and 1^a the framing of the waste collecting machine may be made of ordinary iron tubing coupled where required so as to stand any ordinary strain as the waste collecting apparatus is moved around from place to place, a tubular rod 43, Fig. 1^a preventing any sidewise give of the framing joints and the rods 22 preventing strain on the joints and brackets in a direction lengthwise of the frame structure. The board 39 and another board 39' near the top of the framework bolted to the upright rods increases the rigidity of the frame structure as a whole, and serve as supports for parts of the air induction apparatus.
- To the end of the hose 16 is attached a section of pipe 50 by means of a pin and an inclined slot in a coupling 57 and to the pipe 50 is connected a nozzle slightly flared at its end and connected to the pipe 50 by a pin and inclined slot in the coupling 52. This nozzle is bent as shown at 53 and again as shown at 56, the bent end section being connected to a section 54 by a pin and inclined slot in a coupling 55. I have found the bent and flared nozzle a most convenient arrangement in reaching around obstructions and in collecting waste, dust, etc., on the under surfaces of machine parts. By turning the bent part of the nozzle the flared end may be brought over surfaces at various inclinations to the operator.
- It is obvious that various changes and modifications may be made in the details of construction and design of my machine as specifically described without departing from the spirit of my invention, such changes and modifications being restricted only by the scope of the following claims.
- I claim as my invention:
- An air cleaning apparatus comprising a truck, a braced frame structure including upright rods and inclined brace rods, a waste collecting chamber, a band surrounding the chamber leaving the lower end of the chamber accessible to receive the open end of a bag thereover, brackets on the band sup-

ported by the frame structure, a compressed air pipe and suction pipe communicating with the upper part of the chamber and both pipes supported by the framework, and a 5 waste bag detachably attached to the lower end of the waste collecting chamber and supported by the truck.

2. An induction air cleaning apparatus comprising a frame structure, a support on 10 the frame structure, a horizontal air pipe section having a pressure regulating and reducing valve therein attached to the support, a section of air pipe extending upwardly from the horizontal air pipe section 15 and supported near its upper end, a pressure gauge attached to the air pipe, said pipe terminating in a nozzle and said nozzle inserted in a larger air pipe, an air hose connected to said larger air pipe, rods extending from the frame structure near its bottom and top and passing around said air hose and beyond said valve, and gauge to prevent undue strain on the connection between said air hose and said pipe and protecting said valve and gauge from contacting with the machine being cleaned as described.

3. In an induction cleaning apparatus, a waste connecting chamber, an air pipe extending thereto and terminating in a coil 30 within the chamber, a compressed air pipe terminating in a nozzle inserted into said first mentioned air pipe and located above the bottom of the pipe, the nozzle being inclined upwardly from the bottom of the 35 first mentioned pipe.

4. In an induction cleaning apparatus, an air pipe having a section with its air passage slightly contracted at one end, said end being provided with a projection having a 40 hole therethrough, a compressed air pipe having a nozzle projected through said hole, said nozzle being slightly inclined upwardly to the axis of said first mentioned pipe section to more efficiently draw the air through the 45 air pipe, a waste chamber into which said first mentioned air pipe projects and an inclined shelf within the chamber at the end of the air pipe to direct the air downwardly and thus pack the dust and accumulated 50 waste in the bottom of the waste connecting chamber.

5. In an induction cleaning apparatus, an air pipe terminating in two end to end sections, said sections being smaller at their 55 meeting ends than at their other ends and a compressed air pipe terminating in a nozzle adjacent the meeting ends of the sections, said nozzle terminating on the interior of said first mentioned pipe sections and above the bottom of one section, a waste collecting 60 chamber into which said first mentioned air pipe projects, said air pipe terminating in a coiled portion and gradually inclining downwardly from where the compressed air pipe 65 enters the same to the opposite end of the

coil within the waste collecting chamber to conduct off water of condensation, said waste collecting chamber having a shelf therein with an inclined portion to further direct downwardly the air, dust and waste.

6. In an induction cleaning apparatus, an air pipe having a contracted portion, a compressed air pipe having a nozzle extending into the first mentioned air pipe adjacent its contracted portion and below the same, a waste collecting chamber into which said first mentioned air pipe projects, said air pipe terminating in a coiled portion, and an inclined shelf within the chamber at the end of the coiled portion of the air pipe.

7. In an induction cleaning apparatus, an air pipe into which projects a compressed air pipe, a waste collecting chamber into which the first mentioned air pipe projects and, in which the air pipe terminates in a coil, said pipe being inclined slightly downwardly to carry off any water of condensation that might collect in the pipe, said first mentioned pipe being larger in cross section in its coiled portion and gradually decreasing in size to the place of insertion of the compressed air pipe.

8. In an induction cleaning apparatus, an air chamber, an air pipe extending thereto and terminating in a coil, a compressed air pipe extending into the first mentioned air pipe, a truck, a framework on the truck to support the air pipe and compressed air pipe, and a bag detachably held to the bottom of the waste collecting chamber and supported on the truck.

9. An induction cleaning apparatus comprising a waste collecting chamber, metallic sections of air pipe rigidly connected to said chamber and rigidly supported by a framework, a flexible section of air pipe extending downwardly from the rigid portion of the pipe and coupled thereto, and a projecting part from the framework extending around said flexible section to prevent strain 105 on the coupling between the pipe sections as the apparatus is moved around from place to place.

10. In an induction cleaning apparatus, a truck, a framework carried thereon, a waste collecting chamber carried on the upper end of the framework, a metal section of the compressed air tube and a section of a suction tube communicating with said chamber, the chamber and tubes being held in fixed 115 relation to each other by said framework, a bag between the chamber and truck and adapted to rest on the truck, the chamber having a flange at its bottom portion and said bag being attachable over the flange, 120 and means for holding the bag in attached relation to the flange.

11. In an air induction cleaning apparatus, an elongated truck having upright posts at its rear side, braces for the posts, and a 130

waste collecting chamber carried by the posts, a waste bag adapted to rest on the truck and between the side braces and attachable to and detachable from the lower edge of the waste collecting chamber and removable horizontally from the truck when detached from the waste chamber.

12. In an induction cleaning apparatus, a truck having wheels axially alined near its middle and a third wheel swiveled to its end to permit sudden turns of the truck and a stop to prevent overturning of the truck, a framework supported by the truck comprising upright posts and side braces, said framework carrying a waste chamber at its upper part and metal sections of compressed air and suction pipes communicating with said chamber, the parts being held in fixed relation with each other by said framework and a waste bag attachable to and detachable from the lower end of the waste chamber and removable horizontally without lifting it from the truck as described.

13. An induction cleaning apparatus comprising a truck, a framework carried by the truck including uprights, a metallic air pipe and a compressed air pipe rigidly attached to and supported by the framework, air hose having couplings whereby the same may be attached respectively to the air pipe and the compressed air pipe, said couplings being supported on the framework and said uprights having brace rods extending around the air hose so as to protect the couplings when the induction air cleaning apparatus is moved from place to place.

14. An induction cleaning apparatus comprising a truck, an upright framework extending from said truck, a horizontal section of air pipe having therein a pressure regulating and reducing valve carried by the framework, a vertical section of air pipe with which the regulating valve is connected also carried by the framework, a pressure gauge connected to the vertical section of the air pipe, said framework having a rigid part protecting the air pipe and gauge from injury and also having a projecting part protecting the pressure regulating valve from injury.

15. In an induction cleaning apparatus, a waste collecting chamber closed at its top and open at its bottom and having a band therearound, brackets on the band, a framework for supporting the chamber attached to said brackets, and metallic sections of air pipes extended at one end into the chamber and supported thereby at said end and supported rigidly by the framework at their outer ends.

16. In an induction cleaning apparatus, a waste collecting chamber, a framework for supporting the same, an air pipe rigidly connected to the framework and to the waste

collecting chamber, said air pipe having a clean-out hole and a detachable cover exterior of the chamber and a coiled portion interior of the chamber as described.

17. In an induction cleaning apparatus, an upright rigid framework, a support attached to the lower part of the upright frame and carrying a horizontal section of pipe, a pet cock in the horizontal section of pipe for draining water of condensation therefrom, said framework also carrying at its upper portion a support, and a vertical section of air pipe extending from the horizontal section of pipe upwardly and supported at its upper end by the upper support on the framework.

18. In an induction cleaning apparatus, a truck, a framework supported thereon, metallic pipe sections rigidly attached to the upper part of the framework, flexible pipe sections attachable to the rigid pipe sections by couplings and rigid brace rods from the framework for protecting the couplings from undue strain as the framework is moved from place to place.

19. In an induction cleaning apparatus, a waste collecting chamber and pipe sections rigid therewith, and communicating with the interior of the waste chamber at its upper portion, said waste collecting chamber having a flange at its lower portion and a waste collecting bag having a draw string or cord at its mouth for attaching the bag above the flange of the waste chamber, and a framework for supporting the dust collecting chamber attached to the waste collecting chamber between its upper and lower ends leaving the lower end of the chamber exposed for the attachment of the bag.

20. In an induction cleaning apparatus, a waste collecting chamber having a bag attached thereto, pipe sections ending in a coil in the interior of the waste chambers at its upper portion and an inclined shelf on the interior of the chamber terminating in an inclined portion to direct the waste particles downwardly and pack them in the bag.

21. In an induction cleaning apparatus, an air pipe having a contracted portion and extending beyond the contracted portion a flared portion ending in a coiled portion, a compressed air pipe having a nozzle extending into the first mentioned air pipe below its contracted portion, a waste collecting chamber enclosing the coiled portion of the air pipe, said chamber being bottomless, with a flange at its bottom portion adapted to receive and hold the mouth of a bag held to the chamber by a draw string above the flange.

In witness whereof I hereunto affix my signature.

ROBERT P. SWEENEY.
